UNITED STATES PATENT OFFICE.

VICTOR SIMONIN, OF CAMDEN, NEW JERSEY.

TOBACCO-PIPE.

1,080,851.

Specification of Letters Patent.

Patented Dec. 9, 1913.

Application filed September 19, 1911. Serial No. 650,079.

To all whom it may concern:

Be it known that I, VICTOR SIMONIN, a citizen of the United States, residing at Camden, in the county of Camden and State 5 of New Jersey, have invented certain new and useful Improvements in Tobacco-Pipes, of which the following is a specification.

This invention relates to tobacco pipes, and has for an object to provide a combined 10 cooling and collecting chamber therefor in which the nicotine and saliva will be arrested and the smoke permitted to circulate in a large volume so as to become thoroughly cooled before its final passage to the exit 15 duct of the pipe stem.

Another object of the invention is to provide a pipe wherein the combined cooling and collecting chamber can be readily removed from the pipe and its parts cleaned 20 and thoroughly sterilized if desired.

Another object of the invention is to provide a construction which will include a novel form of attaching means whereby the chamber can be securely applied to the pipe.

In the drawing, forming a portion of this 25 specification and in which like numerals of reference indicate similar parts in the several views:—Figure 1 is a side view of the pipe. Fig. 2 is a longitudinal section there- 30 through.

The pipe herein shown is provided with a bowl 1 which may be of any suitable well known configuration, the same having formed integral therewith the stem 2 to 35 which the mouthpiece 3 of the pipe is removably fitted.

The combined cooling and collecting chamber comprises preferably a glass tube 4 which has one of its ends fitted in a correspondingly formed recess 5 in the stem 2 at a point in juxtaposition to the bowl. Through 40 this arrangement of the chamber the latter is exposed sufficiently to the outside air to become chilled thereby to thereby effect a rapid and thorough cooling of the smoke as 45 it passes from the bowl. The tube 4 can be constructed of any desired size which may be found most suitable for the purpose. A post 6 extends centrally through the tube 4, the lower end 7 of the post being threaded 50 exteriorly and detachably fitted in a correspondingly threaded passage in the stem 2. The upper end of the post extends beyond the top of the tube 4, being exteriorly thread-

ed, at 8, to receive the interiorly threaded 55 cap 9, as illustrated.

The cap 9 is provided with a relatively large base 10 which effectively fits against the upper open end of the tube 4 so as to close the same. The base 10 is provided 60 with a short annular flange 11 which embraces the upper end of the tube 4 so as to insure a suitable connection at this point to prevent the escape of the smoke at this end. The post 6 is constructed of bone, prefer- 65 ably, but it is obvious that any suitable well known material which may be found most desirable may be used as a substitute therefor. The post is provided with a longitudi- 70 nal bore 12 and the discharge perforations 75 13, the perforations 13 are disposed radially with respect to the longitudinal axis of the post and they are located preferably at a point adjacent to the base 10 of the cap 9. The bore 12 of the post opens into the dis- 75 charge duct 14 in the stem 2, the latter being operatively arranged in the required communication with the duct in the mouth- 80 piece of the pipe. The walls of the post 6 are spaced from the walls of the tube 4 so as to define therewith an intervening chamber 85 of a capacity capable of receiving a large volume of smoke. The glass tube is open at both ends, the lower end of the same being in communication with the branch duct 15 in the stem 2. The duct 15 extends down- 90 wardly substantially at an obtuse angle with respect to the axis of the post 6, the intake end of the duct opening directly into the tobacco chamber of the bowl 1 at the lower end 90 thereof. An absorbent saliva and nicotine or moisture collecting cartridge 16 embraces the post 6 and is so positioned in the tube as to thoroughly collect such saliva and nicotine as may be drawn into the tube 4 by way of 95 the duct 15. The cartridge has its upper end disposed slightly below the plane of the radial discharge perforation 13 so as to not obstruct the passage of the smoke as it is drawn into the stem of the pipe. 100

By providing a device of the nature de- 105 scribed herein a practically perfect sanitary arrangement is had, whereby the smoker can enjoy the use of his pipe without experiencing the customary biting of the tongue which arises generally in smoking pipes.

The device, while being of a decidedly simple character, is capable of rapid appli-

cation to the pipe or removal therefrom so that all of its essential elements can be thoroughly cleaned at the will of the user.

I claim:

- 5 The combination with a pipe having its stem provided at a point adjacent to the bowl with a threaded passage and a relatively large recess opening into said passage, a post extending from said passage and threaded to fit therein and rising from the stem and provided through a portion of its length with a smoke-conducting bore having a lateral branch opening onto one side of the post, a circular tube embracing said post
- 10 and lying wholly within the ends thereof and spaced vertically from the sides of the post and seated at its lower end in said recess, an absorbent cartridge extending around said post, said post having a thread-

ed portion extending above the tube, and a closure fitted to said threaded portion and extending entirely over the upper end of the tube and operable to bear thereagainst to seal the joints between the closure and said tube and operable also to advance the lower end of the tube against the bottom wall of the recess to seal the joint between the stem and tube respectively, the stem having a duct leading from the bowl to the tube and a duct leading from the bore of the post to the mouth-piece of said pipe.

In testimony whereof I affix my signature in presence of two witnesses.

VICTOR SIMONIN.

Witnesses:

CHARLES SIMONIN,
Wm. SCHMID.
